UNITED STATES PATENT OFFICE.

DAVID ALEXANDER McCOWAN, OF TORONTO, ONTARIO, CANADA.

VENDING-MACHINE.

1,393,147.

Specification of Letters Patent. Patented Oct. 11, 1921.

Application filed June 30, 1919. Serial No. 307,766.

To all whom it may concern:

Be it known that I, DAVID ALEXANDER McCOWAN, a subject of the King of Great Britain, and resident of the city of Toronto, 5 county of York, Province of Ontario, in the Dominion of Canada, have invented certain new and useful Improvements in Vending-Machines, described in the following specification and illustrated in the accompanying 10 drawings, that form part of the same.

The principal objects of this invention are, to devise a vending machine of extremely small, neat and attractive appearance which will be proof against fraudulent operation 15 and when empty automatically prevents the insertion of coins.

A further object is to permit the owner to ascertain the number of packages remaining in the box at any time without the necessary of opening the box.

The principal feature of the invention consists in the novel construction and arrangement of parts, whereby the package is delivered by the operation of pivotal members connected with a pivotal arm and said pivotal arm is operated by means of a pivotal member temporarily locked in engagement with said pivotal arm by the operating coin.

30 A further important feature consists in the arrangement of a registering device adapted to be operated by the movement of the pivotal arm in the release of the packages and the operation by said registering 35 device of means for locking the pivotal operating member from further operation following the delivery of the last package.

In the drawings, Figure 1 is an elevational view showing the mechanism in the position 40 of rest ready to receive a coin.

Fig. 2 is an elevational view showing the position of the parts after the insertion of the coin in the operating position releasing the package.

45 Fig. 3 is an elevational view showing the position of the parts when the device has been locked after having released the last package.

Fig. 4 is a vertical sectional view through 50 the line $\alpha-\alpha$ of Fig. 1.

Fig. 5 is a perspective detail of the coin receiving operating pivotal member.

The casing 1 of the machine is preferably of oblong rectangular form and is adapted 55 to be decorated to represent a package of

the goods to be sold. The front wall 2 is provided with a coin slot 3 of the proper dimensions to allow the insertion of the required coin.

Secured to the inner face of the front wall 60 perpendicularly below the slot 2 is a block 4 which forms a support for one end of the pivot pin 5 which is supported at its other end by a cross bar 6 extending between the side walls of the casing.

65 A metal bar 7 is pivotally mounted intermediate of its length on the pin 5 and its outer edge swings close to the inner surface of the front wall.

The bar 7 is formed with a longitudinal 70 slot 8 opening outwardly through the top and the upper end 9 of the slot is wider than the lower portion. The leg 10 of the bar 7 adjacent to the front wall of the casing is formed with a slot 11 which registers 75 with the coin slot 3 in the casing.

An arm 12 corresponding in shape to the longitudinal slots 8 and 9 of the bar 7 is pivotally supported within said slot on the pivot pin 5 and is adapted to swing on said 80 pivot independent of the bar 7. This arm is formed with a bifurcated upper end, one leg of which extends upwardly beyond the end of the bar 7 and the other leg is shorter.

The slot 13 formed between the legs is 85 adapted to receive the coin inserted through the slot 3 to form a coin pocket and the edge of the coin extends into the slot 11 and forms a locking engagement between the arm 12 and the bar 7.

The arm 12 is formed with a slot 14 in the short leg which extends to the top thereof and a corresponding slot 15 is arranged in the long leg but terminates adjacent to the top thereof.

90 A spring arm 16 is secured to a bracket 17 arranged on the inner side of the front wall 2 and extends upwardly having a block 18 secured to the upper end. This block is formed with a beveled face 19 and has a narrow spur 20 which extends into and through the slots 14 and 15. The block is adapted to be held in sliding engagement with the face of the arm 12 as it swings on its pivot and the spur slides along the slots 105 therein to eject coins in a manner herein-after more fully described.

A spring 21 extends between the bar 7 and the side wall of the casing and holds the pivotal bar 7 at the lower end in en- 110

gagement with the lug 22 of the bracket 17 and when in this position the coin slot 11 registers with the coin slot 3.

A plate 23 extends in an arc shape from 5 the bar 7 to cover the coin slot 3 when said bar has been swung upon its pivot to prevent the insertion of another coin until the bar returns to its normal position.

A latch arm 24 is pivotally mounted on 10 a pin 25 and has a spur end extending through the slot 15 of the arm 12 and the underside of the arm is provided with a plurality of ratchet teeth 26 which are adapted to engage the upper edge of the coin 15 when inserted in the holder, preventing the return of the pivotal arm to its normal position until the coin has been ejected from the holder.

A cord 27 is secured to the upper end of 20 the arm 12 and extends out through a hole in the side of the casing and is adapted to be pulled by the person operating the machine after the coin has been inserted. If this cord has been pulled prior to the insertion of the coin, the arm 12 simply swings back and forth on its pivot without moving the bar 7 but when a coin is inserted into the pocket and the bar 7 is locked the pulling of the cord pulls the bar 30 7 on its pivot, thus bringing the edge of the coin into engagement with the ratchet teeth on the latch arm 24. As the bar is pulled to its limit the block 18 slides upwardly and pushes the coin out of the pocket, discharging it at one side of the machine into a pocket 28 where it falls against a spring 35 arm 29 which curves forwardly and lightly engages the front wall of the casing sufficient to hold the coin from passing through. 40 An orifice 30 is arranged in front of the casing opposite to the lower end of the spring arm 29 to disclose the coin that has been liberated from the operating lever.

The packages of goods to be sold are arranged in vertical guides 31 and at the bottom of these guides are arranged a pair of right angular-shaped brackets 32 which support the packages.

The brackets are supported on the pivots 50 33 and are adapted to swing downwardly and outwardly. The swinging operation is conveyed to the brackets from the bar 7 by the links 34 and 35 which are connected to said bar at opposite sides of its pivot.

55 The upper leg of each of the brackets is provided with a small spring 36 which engages the ends of the package above the lower one and holds all but the lower package carried in the brackets from movement 60 while the brackets are being operated. This feature is clearly shown in Fig. 2 where the brackets are illustrated as partly moved in the operation of discharging the lower package.

65 A shutter 37 is pivotally supported in the

lower portion of the casing and extends in the space beneath the brackets 32.

A cord 38 connects the said shutter with the link 34 at its point of connection with the member 7 and as the member 7 swings 70 on its pivot it pulls upwardly on the shutter so that it intercepts the package in falling from the brackets, thereby preventing the package from jamming and assuring its proper delivery.

A registering mechanism is provided in the form of a disk 39 rotatably secured to the inner side of the front wall 2 of the casing. The outer face of this disk is provided with numbers indicating the number of 80 packages contained in the machine. A hole 40 is provided in the front of the casing to disclose these numerals. The disk 39 is provided with ratchet teeth 41 on its periphery which are engaged by a spring latch 85 42 arranged in the lower end of the member 7. This latch engages the teeth of the disk as the member 7 is swung on its pivot and rotates the disk changing the numeral displayed through the hole 40.

A shutter 43 is arranged between the disk and the wall of the casing, such shutter having an opening 44 therethrough. The shutter is carried upon a rod 45 secured to a vertically slid able bar 46 arranged in the 95 bracket 17. The bar is moved upwardly and is adapted to be interposed between the lug 22 on the bracket 17 and the pivotal bar 7. This prevents the bar from swinging back to its normal position as is illustrated in 100 Fig. 3.

The upward movement of the locking member is effected by means of a spring arm 47 secured to the inner face of the disk which engages the rod 45 and lifts it upwardly 105 concurrently moving the vertical lock bar 46 and the shutter 42.

When the bar 7 is in the position described with the bar 46 interposed between it and the stop bracket the coin slot in the bar 7 remains out of register with the coin slot 3 and the slot 3 is covered by the plate 23.

A rod 48 is secured to the latch 24 to the outward side of its pivot and extends downwardly and engages the coin holding spring 115 arm 29 to release the coin previously inserted. The coin then falls down into a suitable coin pocket 49.

In the operation of this device the person desiring to obtain an article contained within 120 the machine inserts the proper coin through the slot 3. The coin falls into the coin pocket arranged in the bar 7 and locks the arm 12. The cord extending through the side of the casing is then pulled and the bar 7 is swung on its pivot to tilt the brackets 32 and release the lower package contained within the guides, the remaining packages being held by the spring members as described. As the bar 7 swings on its pivot the 125 130

block 18 carried on the spring arm 16 forces the coin upwardly until at the end of its stroke it is cleared from the pocket and falls between the spring arm 29 and the front wall 5 of the casing, where it is held for inspection behind the orifice 30.

Upon the release of the coin the bar 7 immediately swings back to its original position and the packages contained within the guides 10 are released and the lowermost package rests upon the brackets 32 and when the cord is released the member 12 swings back to its normal position.

The counting disk 39 is partially rotated 15 with each movement of the bar 7 and indicates the number of packages that have been sold so that a person may easily ascertain how many are still left in the machine and when the last of the articles to be sold is dispensed the locking bar 46 operates in the 20 manner described.

A vending machine such as described is extremely simple. It is positive in its action and is not likely to get out of order.

25 What I claim as my invention is:—

1. In a vending machine, the combination with means for delivering packages one at a time, of a bar pivotally supported and operatively connected with the delivery means 30 and having a slot therethrough extending upwardly from the pivot and a transverse slot in one side intersecting the aforesaid slot, an arm mounted upon said pivot within the slot in said bar and having a slot therein 35 adapted to register with the transverse slot in said bar and adapted to receive a coin, said arm having a longitudinal slot intersecting the coin slot therein, manually operated means for swinging said arm on its 40 pivot and through a coin swinging said bar, and means for dislodging the coin from the coin slots.

2. In a vending machine, the combination with means for delivering the packages one 45 at a time, of a bar pivotally supported intermediate of its length and operatively connected with said delivery means, said bar being slotted at its upper end and having a transverse coin slot in one of the legs thereof, 50 an arm pivotally mounted within the slot in said pivotal bar and having a coin slot registering with the slot in the leg of the pivotal bar and having a transverse slot therethrough intersecting said coin slot, means 55 for swinging said arm on its pivot and through the coin operating said bar therewith, and means for discharging the coin.

3. In a vending machine, the combination with means for delivering the packages one 60 at a time, of an arm pivotally supported and operatively connected with said delivery means, said arm being slotted at its upper

end and having a transverse coin slot in one of the legs thereof, an arm pivotally mounted within said pivotal bar and 65 having a coin slot registering with the slot in the leg of the pivotal bar and having a transverse slot therethrough intersecting the coin slot, a spring arm engaging the pivotal arm carried on said pivotal bar, said 70 spring arm having a spur extending into the transverse slot in said arm and adapted upon the swinging of the bar to push the coin clear of the coin pocket, and a ratchet arm engaging the top of the coin to prevent the 75 return of the pivotal arm until the coin is released.

4. In a vending machine, the combination with means for delivering the packages one at a time, of a bar pivotally mounted and 80 operatively connected with said delivery means, coin controlled means for moving said bar to release the packages, a spring adapted to return said bar to its normal position following the release of the coin, means 85 for recording the discharging of the packages operated by the movement of the said pivotal bar, an arm arranged to move into contact with said pivotal bar to prevent its return to normal, and means carried by said 90 recording member for obstructing said bar.

5. In a vending machine, the combination with means for delivering the packages one at a time, a bar pivotally mounted and operatively connected with said delivery means, 95 a rotatable disk having numerals on its face and a ratchet toothed edge, a latch carried on said pivotal bar adapted to engage the teeth on said disk, a spring latch arranged upon said disk, a vertically slid able arm having an extension portion adapted to be engaged by said spring latch on said disk to move the slid able arm into engagement with the pivotal bar, a casing inclosing the mechanism having a hole arranged opposite a portion of said disk to disclose the numerals one at a time, and a shutter carried on said 100 vertically movable arm.

6. In a vending machine, the combination with means for delivering the packages one 110 at a time, of a bar pivotally mounted and operatively connected with said delivery means, coin controlled means for moving said bar to release the packages, means for disengaging the coins on said coin controlled means, a pocket adapted to receive the coin, a spring arm in said pocket adapted to arrest the coin, a casing inclosing the mechanism, a hole arranged in the casing opposite said spring arm adapted to disclose 115 the coin, and means operated by the succeeding movement of the pivotal bar for releasing said coin from the spring arm.

DAVID ALEXANDER McCOWAN.
